UNITED STATES PATENT OFFICE.

LOUIS A. MACKLANBURG, OF OKLAHOMA, OKLAHOMA.

WEATHER STRIP.

Application filed April 29, 1922. Serial No. 557,253.

To all whom it may concern:

Be it known that I, LOUIS A. MACKLANBURG, a citizen of the United States, residing at Oklahoma city, in the county of Oklahoma and State of Oklahoma, have invented certain new and useful Improvements in Weather Strips; and I do hereby declare the following to be a full, clear, and exact description of the invention, such as will enable others skilled in the art to which it appertains to make and use the same.

This invention relates to strips of springy sheet material adapted to be secured between the edge of a sash, door or other closure and its frame for the purpose of excluding dust and air currents.

An object of the invention is to enable elastic metallic weather strips to be secured by nails or other headed fastenings without leaving the heads protruding above the general surface of the strip and without the necessity of performing countersinks in the strip.

The object is attained in a transversely elastic metallic strip having a suitable offset edge, or suitable edges, for engaging with a relatively movable member, and having an embossed or rolled rib in relief, or convexed on the face of the strip, extending longitudinally thereof along the zone through which the nails or other headed fastenings are driven to secure the strips in place. Nails driven through this transversely convexed zone may be sunk beneath the general surface thereof by the final blow of the hammer thus depressing the material around the nail head while the spaces left between the sunken heads of the nails serve as a cushion and guide means for the relatively movable member, such as the edge of a sash, even should the elastic engaging portion of the weather strip be forced in so far that the edge of the movable member contacts with the embossed rib.

In the accompanying drawings in which corresponding reference characters designate corresponding parts throughout the several views:

Figure 1 is a cross section through a piece of weather strip made in accordance with this invention;

Figure 2 is a cross section through a fragment of a window casing and sash illustrating the improved weather strip nailed to the casing;

Figure 3 is a view of a fragment of

weather strip nailed in place looking at the face;

Figure 4 is a longitudinal section on the line 4—4 of Figure 3;

Figures 5 and 6 are cross sections of a slightly modified form;

Figures 7 and 8 are cross sections of a further modified form, and

Figure 9 is a cross section of still another form.

Referring to the drawings, 1 indicates a portion of a window casing; 2 the usual window stop; 3 the separating strip, and 4 one of the stiles of a sash. W indicates, as a whole, an elastic weather strip, shown in Figure 2, as nailed to the window casing within the groove lying between the stop 2 and the separating strip 3, the offset edge of said strip engaging the stile and sealing the space against the entrance of air currents and dust. The weather strip W may be composed of a thin piece of hard sheet brass or other suitable springy material formed by suitably fluted, ribbed or grooved bending rolls so as to have a rib transversely convexed or embossed, to form a rolled zone 10 in relief on the face side of said strip and a corresponding groove or channel on the back side thereof. When this strip is nailed in place the edge 11 and the bead 12 on the back side of the strip bounding the channel come in contact with the base to which it is nailed, usually the window casing. Extending from the rib 12 obliquely outward and forward, away from the base, is the relatively broad elastic portion 13 at the edge of which is a recurved bead 14 the convex face of which is intended to engage with the sliding member,—as with the inner edge of the stile of a window sash. Thus a smooth bearing surface is provided for the stile and sharp edges which would cut into and wear the wood are avoided. The strip is secured in place usually on the window casing between the stop 2 and separating strip 3 by driving nails 15 at intervals through the embossed convexed zone 10. The final blow of the hammer in driving the nail home causes the head of the nail to depress the region surrounding it and sinks the head of the nail below the normal surface of said embossed ridge as shown in Figures 2, 3 and 4. Between the heads of the several nails or other fastenings which secure the weather strip in place the metal of the embossed portion will retain its orig-

inal position and if the stile 4 should be pushed in against the bead 14 so far as to come in contact with the embossed portions of the strip between the nail heads there will be no heads projecting to engage with the stile and cut, or wear it, or catch on it to render the opening and closing of the sash difficult.

The preferred form of my weather strip is that which is illustrated in Figures 1, 2, 3 and 4. Various modifications thereof may be made, however, that preserve the principal feature of utility adapting the weather strip to be nailed in place, without the previous formation of countersunk portions, whereby the driving of the headed fasteners causes them to sink into a convexed embossed portion and bury their heads below the face surface thereof. In Figures 5 and 6 the embossed portion 10^a is rounded in cross section and the strip is shown as ribbed or longitudinally embossed along parallel lines, as at 16 and 17, principally for the purpose of rendering the strip stiffer longitudinally in order to prevent it from bending over and to make it more convenient for handling during nailing. In the form shown in Figures 7 and 8 the embossed or rolled nailing zone 10^b forms approximately a wide angle in cross section and when nails are driven through this embossed zone 10^b the material immediately surrounding the nail head when the latter is driven home will be flattened out while the portion of said embossed zone between the nail heads will retain substantially its original ribbed form except for the distortion produced adjacent the nail head.

Although I prefer to use a strip nailed adjacent one edge, the free obliquely projected edge elastically engaging the edge of the stile or other relatively movable member, the weather strip may be made transversely curved in cross section, of symmetrical contour, having two recurved engaging edges as illustrated in Figure 9 with a central rolled or embossed portion 10^c convexed on the face of the strip, extending longitudinally midway between the stile engaging edges and forming a convexed ridge or zone along the middle of the face side of the strip. Nails or other headed fasteners driven through the nailing zone 10^c to secure the strip to the casing will depress the embossed ridge at and around the head so that the outer surface of the head will be sunk below the general surface of the rib and the effect will be the same in so far as the countersinking of the fastener heads is concerned as in the other forms.

Although it is contemplated that the improved weather strip shall be secured by nails or screws to the casing of a sliding door or window, it will be obvious that the benefits of this improvement may be ob-

tained by nailing or screwing the strip to the edge of a sash or door.

Having described my invention in such manner as to enable those skilled in the art to make and use the same what I claim and desire to secure by Letters Patent is:

1. A weather strip of thin, springy material having a convexed zone for the reception of means for securing said strip in operative position, the thickness of the material in said zone being so related to the elasticity thereof that only the portion immediately adjacent the securing means is depressed when the latter is forced to operative position.

2. A weather strip of resilient sheet metal having a longitudinally extending zone of convex cross section for the reception of means for securing said strip in operative position, the thickness of the material in said zone being so related to the elasticity thereof that only the portion immediately adjacent the securing means is depressed when the latter is forced to operative position.

3. In combination with a casing member and a closure member movably mounted therein, a weather strip of thin springy sheet material carried by one of said members having an embossed zone in relief along the face of the strip and headed fasteners penetrating the embossed zone and seated in said member having their heads depressed below the general surface of said relief zone and holding only the material around said heads depressed and in contact with said member.

4. In combination with a casing member and a closure member movably mounted therein, a weather strip of thin springy material having an embossed zone in relief along the face of the strip and longitudinally spaced headed fasteners penetrating the embossed zone and seated in one of said members having their heads depressed below the general surface of said relief zone and holding only the part of the zone around said heads depressed and in contact with said member.

5. A weather strip of springy sheet material having an embossed zone in relief extending longitudinally on the face thereof the thickness and resiliency of the material in said zone being so related that headed fastenings may be driven therethrough to secure said strip in place without depressing any portions of said zone except those immediately around said fasteners, and a resilient engaging portion extending obliquely forward and having a recurved free edge the convex face of which is adapted to engage a relatively slidable member.

In testimony whereof I affix my signature.

LOUIS A. MACKLNBURG.
